MODULAR RESTAURANT

Edward M. Laigo, Tacoma, Wash., assignor to
Burger Box, Inc., Fife, Wash.

Filed Nov. 7, 1973, Ser. No. 413,556

Term of patent 14 years

Int. Cl. D25—03

U.S. Cl. D13—1 B

FIG. 1

FIG. 2

FIG. 3

FIG. 4

FIG. 1 is a top perspective of a restaurant embodying my design;

FIG. 2 is a front elevation of the restaurant of FIG. 1;

FIG. 3 is a side elevation of the restaurant of FIG. 1; and

FIG. 4 is a top plan view of the restaurant of FIG. 1. The rear and other side of the restaurant not shown are identical to the side shown in FIG. 3.

I claim:

The ornamental design for a modular restaurant, as shown and described.
